Term of patent 14 years

Claims priority, application Switzerland Oct. 14, 1960

(Cl. D42—8)

FIG. 1 is a top plan view of a wrist watch case showing my new design;

FIG. 2 is a left-side elevational view thereof;

FIG. 3 is a right-side elevational view thereof;

FIG. 4 is a rear elevational view thereof; and

FIG. 5 is an end view thereof.

The essential feature of my design resides in the combination on the wrist watch disclosed of the integral upstanding crown guards rising in sweeping curves from the strap lugs of the case, substantially as shown.

I claim:

The ornamental design for a wrist watch case, as shown and described.
